Patented Nov. 24, 1914.

UNITED STATES PATENT OFFICE.

WILLIAM J. POWELL AND STANLEY M. PONTIERE, OF OCEAN CITY, NEW JERSEY;
SAID PONTIERE ASSIGNOR TO SAID POWELL.

BOWLING-GAME APPARATUS.

1,118,877.

Specification of Letters Patent. Patented Nov. 24, 1914.

Application filed January 29, 1914. Serial No. 815,231.

To all whom it may concern:

Be it known that we, WILLIAM J. POWELL and STANLEY M. PONTIERE, citizens of the United States, residing at Ocean City, in the county of Cape May and State of New Jersey, have invented new and useful Improvements in Bowling-Game Apparatus, of which the following is a specification.

The invention has for an object to introduce a new element of novelty into a bowling game, as well as to provide a new and simple means for resetting a plurality of pins or the like.

An important object is to provide a means for indicating in a humorous manner when, in a game where a group of pins are to be bowled at, the ball fails to strike any of the pins.

An important object is to enable the simple mounting of such a device and also to provide for its resetting coincidently with, and with the same mechanism that operates, the pins.

Other objects and advantages will appear, some of which will be apparent from the following description, and from the drawings, in which,

Figure 1 is a top view of a game constructed in accordance with my invention. Fig. 2 is a side view thereof. Fig. 3 is a longitudinal sectional view. Fig. 4 is a cross section thereof. Fig. 5 is a detail of the miss indicator. Fig. 6 is a further detail thereof. Fig. 7 is a detail of a pin steadyng device.

There is illustrated a game comprising an alley formed by two side walls 10 and a bowling floor 11, at each side of which there are formed valleys 12 similar to those familiar in other like games. While the alley may be built into the floor of a hall or other place, the device as illustrated is shown in such form as to be adapted to be set upon a floor already constructed, whether intended for such purpose or not. The alley is supported by a suitable number of legs 13 secured to each side of the alley. The floor 11 is provided with a plurality of longitudinal slots 14 at its rear end, opening through the top and bottom and on the rear end, all having the same length. Immediately beneath the forward ends of these slots there is mounted a shaft 15 having its ends secured in the walls 10. On this shaft

there are mounted pin elements 16, comprising a base portion 17 of rectangular form fitted slidably in the slots respectively, movable pivotally to lie with their upper ends flush with the top of the floor 11. Formed integrally on the outer ends of the members 17 or attached thereto there are respective pin portions 18 corresponding in form to ten-pins or having any other desired configuration. The bottom portions 17 of the pin elements have an extension 19 below the shaft 15, which may be extended diagonally toward the rear side of the portions 17 if desired. Pivoted upon the shaft 15 outwardly of the pin elements there is a resetting yoke 20 having a transverse bar 21 spaced from the shaft and held at the forward and upper limit of its movement by means of a spring or springs 22. The bar 21 is so disposed as to be engaged by the extensions 19 of the pin elements when the upper portions of the pin elements fall rearwardly. Connected to the bar 21 there is a cable 23 extending rearwardly through a pulley 24 suitably mounted below the level of the floor 11, thence forwardly a short distance, being connected to the rear end of a sliding rod 25 supported by one or more brackets 26 and having its forward end supported slidably upon the right hand forward leg 13. Incorporated in this rod adjacent the last named leg there is a slotted block 27 receiving the lower end of a lever 28 pivoted at an intermediate point on a suitable bracket 29 fixed to the leg. The upper end of this lever projects above the floor 11 and is adapted to be pressed rearwardly to draw the bar 21 downwardly and rearwardly to force any fallen pin elements into erected position. The bottom of each valley is also slotted at its rear part, and mounted thereon there is a valley pin 30, having a knobbed upper end, this pin being normally inclined forwardly with the knob so disposed as to engage any ball which fails to strike one of the pin portions 18. Connected to this pin 30 so as to be raised into view when the pin is moved by a ball there is an indicator 31, preferably having some amusing shape, such as that of a monkey, as in the present case. As shown, the monkey is mounted in a recess 31' formed in the wall 10 and opening on the upper side thereof, being fixed upon a sleeve 32 which is engaged

revolubly on the shaft 15, and attached to the pin 30. It is found preferable to mount the pin directly on this sleeve by boring the pin to permit the sleeve to be engaged therethrough. The pin 30 also has an extension at its lower part 19', adapted to be engaged by the bar 21 and moved to initial position at the same time with the pin element 16. Under this movement the pin 30 is reset, and the monkey moved downwardly into the recess 31', thus being concealed from sight. Mounted over the alley closely adjacent the pin elements there is a bridge 33 having a set of figures indicating the respective values in points for knocking down the various pins. If desired, this bridge may carry a series of spring elements 34, shaped and disposed to bear upon the upper ends of respective pins when erect, so as to frictionally hold them against being upset accidentally, through vibration, this detail being illustrated in Fig. 7. It is not thought that this will be required, however, if the shaft 15 is engaged with the pin element slightly to the rear of their center of gravity, as shown in Fig. 3.

The walls 10 are extended rearwardly of the floor 11 and elevated slightly, as at 35, the rear end being closed in a suitable way, 30 and provided with a suitable padding 36 extending downwardly below the level of the floor 11, being inclined forwardly both at the top and bottom, an inclined floor being provided therebeneath and a partition 35 38 being erected immediately adjacent the rear end of the floor 11, whereby the walls are directed to an opening 39 in the partition, from which they drop upon a return alley 40 extending forwardly at a slight inclination so that the balls are returned to a point conveniently within reach at the forward end of the alley. The sides of the space between the padding and the partition are of course closed. If desired, a netting 45 may be extended forwardly from the upper edge of the padding, whereby balls will be caught if they fly upwardly after striking the pins. It is not believed that the latter is required, however.

It may be found desirable to locate the miss indicator at some other point than that shown, and I do not regard my invention as limited to the specific showing in this application, but to include such changes as the 55 use of an indicator of this nature at any desired point, and the use of suitable connections between it and an actuating element in the valley.

It will be appreciated that the construction of the resetting mechanism is very efficient and economical and liable in a minimum degree to derangement, a single shaft serving for all the pins and the resetting yoke 20.

A ball 41 is used, having a proper

diameter for bowling, not less than the space between the centers of two adjacent pins, preferably.

What is claimed:

1. A game of the class described comprising an alley having a floor, slotted at its rear end, a horizontal shaft mounted beneath the slots, a plurality of pins mounted on the shaft for oscillation in respective slots and having extensions projecting beneath the shaft when the pins are elevated, a yoke member pivoted on the shaft and having a transverse bar spaced within the radius of said extensions, resilient means holding the bar at the forward limit of its movement, means for moving the yoke for engagement with the extensions, and a ball for projection along the alley and engagement against the pins. 70

2. A game of the class described comprising an alley having a floor and valleys at each side, a plurality of longitudinal slots being formed in the floor, a slot being formed in each valley, a horizontal shaft extending transversely of the slots therebeneath, pin elements in respective slots pivoted on the shaft for oscillation under impact of a ball, an indicator device connected to the pin in each valley for elevation under engagement of the pin by a ball, means to conceal said indicator when at the lower limit of its movement, a yoke member pivoted on said shaft and having a transverse bar in the plane of oscillation of all the pins, spaced from said shaft, all of the pins having extensions below the shaft of greater radius than the bar and adapted to engage the bar, resilient means to hold the bar at one limit of its movement to be engaged by the extensions of the pins when upset, means to oscillate said yoke to reset the pins and indicator, and a ball for the purpose described. 90

3. In a bowling game apparatus, an alley structure having a floor space for the erection of target elements, and spaces laterally of the first named space for the passage of projectiles clear of the target elements, a yielding movable member in each of the lateral spaces, an indicator connected thereto for movement over a predetermined distance, means to conceal the indicator in initial position, and means to reset the indicator and said movable member after operation. 100

4. In a bowling game, an alley structure including a floor having a valley formed at each side thereof, a slot formed centrally of each valley at its rear part, a pin member mounted for oscillation in the slot to project into the valley at times, an indicator device, a recess in the alley structure to receive the indicator device, the indicator being concealed in the recess when the said pin member is projected into the alley, and connec- 120 125 130 135

tions between the indicator and pin member for discovery of the indicator upon movement of the pin member from the alley.

5. In a bowling game apparatus, an alley structure including a slotted floor, valleys at each side and pin members pivoted for oscillation in the slots, a common pivot shaft being engaged through the pin members and projecting beneath the valleys, slots formed 10 in the valleys, a member pivoted on the shaft beneath each valley and oscillable to project into the valley through the slot, a member fixed to the pin and projecting laterally

therefrom, and an indicator, projected from the last named member at an angle to the 15 radius of the said last named pin member and means to reset all of the pin members.

In testimony whereof we have hereunto set our hands in presence of two subscribing witnesses.

WILLIAM J. POWELL.
STANLEY M. PONTIERE.
